UNITED STATES PATENT OFFICE

103,786

DESIGN FOR A COMBINED TRANSPARENT CARTON AND CLEANSING TISSUE DIS- PLAY

William Medoff, Brooklyn, N. Y., assignor to National Cellulose Corporation, New York, N. Y., a corporation of New York

Application April 16, 1936, Serial No. 62,156

Term of patent 7 years

To all whom it may concern:

Be it known that I, William Medoff, a citizen of the United States, residing in Brooklyn, county of Kings, city and State of New York, have invented a new, original, and ornamental Design for a Combined Transparent Carton and Cleansing Tissue Display, of which the following is a specification, reference being had to the accompanying drawing, forming a part thereof.

In the drawing:—

Fig. 1 is a perspective view of my combined transparent carton and cleansing tissue.

Fig. 2 is a side elevation.

Fig. 3 is an end elevation.

Fig. 4 is an end elevation in section showing the transparent wrapping in section.

I claim:—

The ornamental design for a combined transparent carton and cleansing tissue display, substantially as shown.

WILLIAM MEDOFF.
